HINGE DEVICE FOR VENTILATING WINDOWS

Original Filed April 8, 1939

UNITED STATES PATENT OFFICE

2,327,390

HINGE DEVICE FOR VENTILATING WINDOWS

Albert P. Ball, Detroit, Mich., assignor to Briggs Manufacturing Company, Detroit, Mich., a corporation of Michigan

Original application April 8, 1939, Serial No. 266,755, now Patent No. 2,260,133, dated October 21, 1941. Divided and this application May 29, 1941, Serial No. 395,847

3 Claims. (Cl. 16—140)

This invention relates to ventilating windows for vehicle bodies or the like, especially door or side windows of automobile bodies, and particularly to that type of ventilating windows wherein it is desirable to close the window opening by means of separate glass panels capable of being moved in different planes and in different directions into closed or open position. The present application is a division of my co-pending application, Serial No. 266,755, filed April 8, 1939, now 10 Patent No. 2,260,133, dated October 21, 1941.

An object of the invention is to provide a ventilating window of the foregoing type wherein the rear portion of the window opening is closed by an adjustable glass panel which may be raised and lowered, and in which the remainder of the window opening is closed by a separate glass panel hinged at or adjacent its rear upright edge and capable of lateral or swinging movement into and out of closed position.

Another object of the invention is to provide a window of the foregoing character in which common means is provided for guiding the forward edge of the slidable glass panel and for pivotally supporting the swinging glass panel.

A further object is to provide a ventilating window having a rear vertically sliding section and a front pivoted section, the latter being mounted so that its forward upright edge may be swung outwardly a slight distance but not into the air stream to permit air to be exhausted from the interior of the body, and thence the front edge may be swung outwardly into the air stream to direct the flow of air into the car.

A further object of the invention is to provide a ventilating window of the aforesaid type in which the swinging glass panel is frictionally held in its various adjusted positions.

Another object of the invention is to provide a swinging glass panel with hinge or pivot members and in which friction is applied directly to one or more of said members.

The above and other objects of the invention will appear from the following description and appended claims when considered in connection with the accompanying drawing forming a part of this specification.

In said drawing:

Fig. 1 is a fragmentary elevation of the inside of a vehicle door embodying a preferred form of 50 the present invention.

Fig. 2 is a fragmentary elevation, partly in section, on an enlarged scale, of a window corresponding to that of Fig. 1, and showing one form of hinge structure embodying the invention.

Fig. 3 is a horizontal fragmentary sectional view, on an enlarged scale, taken substantially along the line 3—3 of Fig. 2.

Fig. 4 is an enlarged fragmentary elevational view, partly in section and partly broken away, showing a modified hinge structure embodying the invention.

Fig. 5 is a horizontal section taken substantially along the line 5—5 of Fig. 4 looking in the direction of the arrows; and

Fig. 6 is a fragmentary vertical section through the adjustable means for applying friction to the hinge of Figs. 4 and 5.

Before explaining in detail the present invention, it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring now particularly to Fig. 1 of the drawing, there is shown therein the upper portion or section of a vehicle door A embodying the present invention. The door is provided with a rear pillar 10, an upwardly and rearwardly sloping front pillar 11, and a connecting header 12. The door has a window opening formed therein which is adapted to be closed by means of separate glass panels, such as a vertically slidable glass panel 14 and a swinging glass panel 15. Located within the window opening between the adjacent inner edges of the glass panels 14 and 15 is an upright fixed post or partition 16, preferably in the form of a channel member. As shown, the front upright edge of the glass panel 14 is adapted to slide in the lined channel 16 and thus the channel serves as an upper guide for this edge of said glass panel. The rear upright edge of the panel 14 is adapted to travel and be guided in a suitable guide member or channel 18 carried by the rear pillar 10, this channel extending downwardly into the window well.

The swinging glass panel 15 is mounted in a surrounding window frame of conventional construction having a base or bottom portion 20, a forward upwardly and rearwardly extending portion or section 21 and a rear upright or substantially vertical section 22. The frame is sealed by means of a compressible weather strip (not shown) which is formed of rubber or the like and

carried by the window reveal and which extends around three edges of the glass panel 15, having a continuous outwardly projecting lip or extension which extends beyond the body portion thereof and projects into the area behind the window opening to engage the inner face of the frame portions 20 and 21 to seal the window opening at these points. The upright portion or section 22 of the panel frame is hingedly connected to the fixed post or guide member 16.

A conventional window regulator mechanism (not shown) is provided and functions to raise and lower the window glass panel 14 to close and open the rear portion of the window opening.

The swinging glass panel 15 is adapted to be moved outwardly about the hinge or pivot 30 and relative to the post 16 into various adjusted positions. A conventional latch member and handle structure for swinging and locking the panel 15 is shown as a whole at 34.

Referring now particularly to Figs. 2 and 3, there is shown one form of hinge structure embodying the present invention. In the present form, the swinging glass panel 15 having the metal frame 20, 21, 22 is connected with the post or channel 16 which post serves as a guide for the sliding glass panel 14. The rear upright edge portion 22 of the metal frame is formed to provide a longitudinally extending tubular or substantially cylindrical portion 35 which is located within in a longitudinally extending channel or recess 16a formed in the adjacent edge of the post 16. A longitudinally split resilient or compressible friction tube or sleeve 36 is interposed between and frictionally engages the tubular rib-like portion 35 and the channel 16a. The frame 20, 21, 22 has a rubber, felt or other non-metallic lining 37 which receives the upright edge of the glass 15. The channel member or post 16 contains a somewhat similar lining or insert 38 to receive the upright edge of the sliding glass panel 14. As shown, the channel-like insert 38 may be formed of rubber which is felt lined at points which are contacted or engaged by the edge of the glass 14. The upper and lower corners of the frame 20, 21, 22 are preferably reinforced by angles or braces 39 and 40, respectively. These angles, as shown, are preferably secured to the frame members by spot welding and are concealed by the lining material 37 (Fig. 2). The split sleeve or tube 36 is preferably formed of brass and by reason of a relatively tight or snug fit exerts a binding action on the socket 16a and also grips the tube or bead 35 so as to produce the necessary friction between these parts and thereby maintain the swinging glass panel 15 in any of its adjusted positions without the aid of any auxiliary means such as adjustable brackets or other operating and holding means. The swinging glass panel may be held in closed position in any suitable manner, as by means of the manually controlled latch member 34 shown in Fig. 1. The assembled parts 35, 16a and 36 have a snug but sliding fit and are preferably assembled together by sliding the brass tube or sleeve 36 over the tube-like member 35 and then by inserting these assembled parts into the longitudinal recess 16a and sliding the parts relatively to one another. By virtue of the intermediate sleeve member 36 friction is constantly applied to the interfitting male and female members of the joint or hinge throughout substantially its entire length.

A somewhat modified form of hinge or pivot construction for the swinging window, embodying the present invention, is shown in Figs. 4 to

6 inclusive. In this form the swinging glass 150 has a surrounding channel shaped metal frame 151 whose upright inner edge is formed to provide a tubular rib-like male member 152 which telescopes with a correspondingly shaped longitudinally extending female member or socket portion 153 formed in the adjacent upright face of the post or channel member 154. This post serves as a guide for the forward edge of the sliding glass panel 140. The frame or channel member 151 contains a felt, rubber or other non-metallic lining 155 to receive the rear edge of the glass 150. The post or channel member 154 contains a lining 156 similar to the liner 38 of the preceding views which receives the forward upright edge of the sliding glass panel 140. The parts 152 and 153 have a relatively snug fit and are in sliding engagement. They are preferably assembled by sliding the inner or male member 152 longitudinally in the female member 153. The joints at the upper and lower inner corners of the frame 151 are preferably reinforced by angles 157 and 158 respectively, which are secured to the frame by welding, or in any other suitable manner.

Referring now particularly to Figs. 4 and 6, it will be seen that the male tubular member 152 is extended upwardly at 152a beyond the upper edge of the frame 151 and is positioned within a guide sleeve or ferrule 159 located in an opening formed in the vehicle window member 160 and held in place therein by welding or soldering, as shown at 161. An internally threaded ring or washer 162 is preferably secured to the top of the guide sleeve 159 and acts as a guide or locator for a removable externally threaded split sleeve 163 which telescopes over the end 152a of the male tube member and which flares outwardly at its lower end, see Fig. 6. The sleeve 163 has a square or hex head 164 by means of which it is gripped by a wrench or other tool and threaded through the washer 162 and into the guide sleeve or ferrule 159. The internal diameter of the sleeve 163 is such as to fit snugly over the end 152a of the male tube member. By adjusting the sleeve 163 in one direction through the medium of its hex head or nut 164 it can be drawn upwardly and thereby caused to tighten its grip upon the tube 152a. By rotating the nut 164 in the opposite direction the sleeve will loosen its grip upon the tube 152a. In this manner the frictional contact between the parts is increased or decreased dependent upon the direction of rotation of the nut. By thus applying friction directly to the internal or male member 152a of the hinge joint, the swinging panel will be caused to remain in any one of its adjusted positions without the aid of any auxiliary operating and fastening means. By the foregoing means the frictional engagement of the parts can be adjusted as desired. As in several of the preceding views, a suitable hand operated latch or lock mechanism (not shown) may be employed for securing the panel 150 in its closed or non-ventilating position.

From the foregoing it will be seen that I have provided an improved ventilating window construction, which, as shown, has two glass panels which can be manipulated as desired to exhaust air from the vehicle or to direct air into the vehicle, and further a construction in which all joints between the glass panels and the fixed portions of the window frame are sealed.

I claim:

1. In a hinge structure for a swingable glass panel for closing a portion of a window opening

in a vehicle door in which the remainder of said opening is closed by a slidable glass panel and in which a fixed post is located between the adjacent upright edges of said panels whereby to provide a guide for the slidable panel and a support for a portion of the hinge structure; said hinge structure comprising a vertically disposed socket member of substantially C-shaped cross section carried by said fixed post, a vertically disposed tubular rib-like member fitting within said socket member and carried by the swingable glass panel, and vertically adjustable friction means engaging the upper end portion of said tubular rib-like hinge member for maintaining the swingable panel in various adjusted positions with relation to said slidable panel.

2. In a hinge structure for a swingable glass panel for closing a portion of a window opening in a vehicle door in which the remainder of said opening is closed by a slidable glass panel and in which a fixed post is located between the adjacent upright edges of said panels whereby to provide a guide for the slidable panel and a support for a portion of the hinge structure; said hinge structure comprising a vertically disposed socket member of substantially C-shaped cross section carried by said fixed post, a vertically disposed tubular rib-like member fitting within

said socket member and carried by the swingable glass panel, and vertically adjustable friction means engaging the upper end portion of said tubular rib-like hinge member for maintaining the swingable panel in various adjusted positions with relation to said slidable panel, said adjustable friction means including a split sleeve adapted to grip said tubular rib-like hinge member.

3. In a hinge structure for a swingable glass panel for closing a portion of a window opening in a vehicle door in which the remainder of said opening is closed by a slidable glass panel and in which a fixed post is located between the adjacent upright edges of said panels whereby to provide a guide for the slidable panel and a support for a portion of the hinge structure; said hinge structure comprising a vertically disposed socket member of substantially C-shaped cross section carried by said fixed post, a vertically disposed tubular rib-like member fitting within said socket member and carried by the swingable glass panel, said rib-like member having an extension projecting beyond said socket member and swingable panel, and a device carried by a fixed portion of the door and adjustable to frictionally grip said extension to hold the panel in various adjusted positions.

ALBERT P. BALL.
